UNITED STATES PATENT OFFICE

CLARENCE W. MILLER, OF DETROIT, AND GILBERT C. GOODE, OF BIRMINGHAM, MICHIGAN, ASSIGNORS TO CHRYSLER CORPORATION, OF DETROIT, MICHIGAN, A CORPORATION OF DELAWARE

BUS CHASSIS CONSTRUCTION

Application filed September 22, 1930. Serial No. 483,447.

This invention relates to an improved chassis construction particularly for a motor bus.

The main objects of the invention are to provide a chassis of the type which has a centrally located, main longitudinal column on the respectively opposite sides of which are mounted a pair of driving motors; to provide improved motor supporting outriggers from which the motors are suspended so as to be conveniently removable; and to provide overhanging supports of this type from which the motors may be disconnected and removed from the chassis by lowering them from their mounting.

Other objects of the invention are to provide improved spring supporting arms on the central column which extend laterally beyond both sides thereof and form supports for the sprung portion of the chassis; to provide improved outriggers for supporting a bus body which are located in related proximity to the spring supporting arms; and to provide means on the spring supporting arms for reinforcing the outer portions of the outriggers.

Further objects of the invention are to provide an improved shock absorber support; to provide a support of this kind which has end portions registering with the intermediate portions of the springs; and to provide buffers on the end portions of the shock absorber supports for cushioning extreme relative movement between the sprung and unsprung parts of the chassis towards each other.

An illustrative embodiment of our invention is shown in the accompanying drawings, in which:

Fig. 1 is a plan view of a bus chassis embodying our invention.

Fig. 2 is a transverse vertical section taken on the line 2—2 of Fig. 1.

Fig. 3 is a transverse vertical section taken on the line 3—3 of Fig. 2.

Fig. 4 is a transverse vertical section taken on the line 4—4 of Fig. 1.

Fig. 5 is a vertical section taken on the line 5—5 of Fig. 4.

Fig. 6 is a transverse vertical section taken on the line 6—6 of Fig. 1.

Fig. 7 is a vertical section taken on the line 7—7 of Fig. 6.

Fig. 8 is a transverse vertical section taken on the line 8—8 of Fig. 1.

Fig. 9 is an end elevation, partly in section, of the structure shown in Fig. 8, as viewed from the line 9—9 thereof.

Fig. 10 is a transverse vertical section taken on the line 10—10 of Fig. 1.

Fig. 11 is a vertical section taken on the line 11—11 of Fig. 10.

In the form shown, the chassis includes a central longitudinal column 1 having spaced channel bars 2 on its respectively opposite sides, the channel sides of the bars being arranged outwardly. A pair of transverse motor supports 3 are mounted at their intermediate portions upon the upper side 4 of the column 1. The members 3 preferably comprise channel bars and their end portions extend laterally beyond the respectively opposite sides of the column 1. These laterally extending end portions are slightly arch shaped and they have downwardly extending extremities 5 which are substantially parallel to the webs of the channel bars 2 of the column.

The channel side of each motor support 3 extends upwardly as shown in Fig. 3, and a pair of upright gusset plates 6 are secured by rivets 7 to the respectively opposite sides 8 of the channel bars of which the motor supports are formed. The gusset plates of each motor support extend outwardly beyond the opposite sides of the column 1 and they are connected together at their upper ends by a body supporting outrigger 9 which is arranged transversely of the column and which extends outwardly beyond the motor support 3 as shown in Fig. 2. The outriggers having side flanges 10 which are riveted at 11 to the upper edge portions of the gusset plates 6. This construction forms a tubular structure of tremendous strength of the type shown in Fig. 3. The outer curved portions of the motor supporting members 3 are each rigidly connected to their respective outriggers by plates 12 which are riveted at 13 and 14 to the side flanges 10 and 8 of the channels 9 and 3,

respectively. If desired, the plates 12 may be formed integral with the gusset plates 6.

Located between the side flanges of each channel bar 2 of the column 1 are motor mounting brackets 15 of channel shape having side flanges 16 which are riveted at 17 to the flanges of the channel bar 2. The webs of the motor supporting brackets 15 and the webs of the downwardly extending end portions 5 of the motor supporting arms are provided with apertures through which bolts 18 extend for supporting a pair of motors 19 which are suspended from the arch shaped end portions of the motor supporting members, one motor being located on each side of the chassis. These motors may be conveniently installed from beneath the side of the vehicle chassis by raising them into place and they have an unobstructed path through which they may be lowered in removing the motors from the chassis.

Mounted on the lower side of the column 1, somewhat in advance of the motor supports 3 is a transverse spring supporting member 20 having end portions which extend laterally from the respectively opposite sides of the column 1. The member 20 has a planular seat 21 by which it is rigidly secured to the lower side of the column by rivets 22 extending through the lower side flange of the web of the channel 2 and through reinforcing brackets 23 which are riveted at 24 to the web of the channel 2. The member 20 is provided for supporting the rear ends of springs 25 on which the rear axle 26 of the bus chassis is mounted. Spring supporting pivots 27 carried by the outer extremities of the member 20 extend through the eyes 28 of the springs 25 forming pivotal attachments between the member 20 and the springs.

The forward ends of the springs 25 have shackles 29 by which they are pivotally secured to pivots 30 on a transverse spring supporting member 31 which has a planular seat 32 that is rigidly secured by rivets 33 to the lower side of the column 1, as viewed in Fig. 6. The transverse member 31 has outwardly extending flanges 34 on each outer extremity of which the respectively opposite sides of inverted U-shaped brackets 35 are mounted by rivets 36, as shown in Fig. 7. The brackets 35 are elongated at their upper extremities which are located substantially in the plane of the top side of the column 1 and the inner ends of the upper portions of the brackets 35 abut against the side edges of the column 1, as shown in Fig. 6.

Mounted on the top side of the column 1, in registration with the transverse spring supporting member 31, is a transverse body supporting outrigger 37 comprising a channel bar which has a flattened intermediate portion 38 resting upon the top of the column and secured thereto by rivets 39. The outrigger 37 extends outwardly beyond the respectively

opposite sides of the column 1 and the channel side thereof extends downwardly and receives the upper extremities of the brackets 35. The side flanges 40 of the outrigger 37 are riveted at 41 to the sides of the brackets 35. With this construction the spring supporting members 31, which are of heavy metal construction as shown in section in Fig. 7, support the outer portions of the outrigger 37.

The springs 25 of the rear axle of the chassis are suspended in the above described manner from the transverse members 20 and 31. The springs 42 of the front axle 43 are suspended in a similar manner from a transverse member 44 which is substantially identical in construction to the transverse member 20 and the rear ends of the springs 42 are supported by a transverse member, not shown, that is identical in construction to the transverse member 31 and which also supports an outrigger 45 substantially identical to the outrigger 37 shown in Fig. 6. The identity of the various parts of the chassis reduces the cost of construction thereof materially and simplifies the problems of construction and assembling.

Mounted on the upper and lower sides of the column 1, in registration with the front axle 43 of the chassis are upper and lower transverse members 46 and 47, respectively which have planular intermediate sections 48 and 49 secured to the top and bottom sides of the column, respectively by the rivets 17 which secure the parts of the fabricated column together. The end portions of the members 46 and 47 extend beyond the respectively opposite sides of the column 1 and they converge and are secured together by rivets 50 at their outer extremities. The outer end portions of the upper member 46 are similarly shaped and have side flanges 51 to which gusset plates 52 are riveted at 53. The lower edges of the gusset plates 52 are provided with flanges 53' which are located adjacent the lower side of the outer end portions of the transverse member 47 and secured thereto by rivets 54.

The above structure provides a partial enclosure at the outer end portions of the transverse members 46 and 47 in which shock absorbers 55 are located. Each shock absorber 55 has an arm 56 which is pivotally connected by an adjustable link 57 with the front axle 43 of the chassis. Mounted on the outer extremities of the transverse members 46 and 47 are buffers 58 which preferably comprise blocks of rubber and which are located in registration with the central portions of the springs 42 of the front axle. These buffers engage the springs and cushion extreme movement of the sprung and unsprung portion of the chassis towards each other.

The front end of the column 1 is provided with a body supporting outrigger 59 which

comprises a channel bar having a planular intermediate portion 60 which is seated upon and riveted to the top side of the column, as shown in Fig. 10. The outrigger 59 is supported by a transverse member 61 comprising a channel bar having a planular intermediate section 62 which is seated upon, and riveted to the lower side of the column 1. These transverse members extend beyond the respectively opposite sides of the column and the outwardly extending portions of the lower members 61 are inclined upwardly and secured at their extremities by rivets 63 to the side flanges 64 of the outrigger 59 between which they are received as shown in Figs. 10 and 11.

Although but one specific embodiment of this invention has herein been shown and described, it will be understood that various changes in the size, shape and arrangement of parts may be made without departing from the spirit of our invention and it is not our intention to limit its scope other than by the terms of the appended claims.

25 What we claim is:

1. A vehicle chassis including a central, longitudinal frame member, a transverse motor support mounted on said member having arch shaped end portions located on the respectively opposite sides of said member, a pair of motors one suspended from each arch shaped end portion of said motor support, and supporting structure above said motor support extending laterally of said chassis and secured to the outer extremities of said arch shaped end portions.

2. A vehicle chassis including a central, longitudinal frame member, a transverse motor support mounted on said member having arch shaped end portions located on the respectively opposite sides of said member, a pair of motors, one suspended from each arch shaped end portion of said motor support, upright gusset plates mounted on the intermediate portions of said motor support, a body supporting outrigger on the upper edge portions of said gusset plates having end portions in registration with the arch shaped ends of said motor support, and members rigidly connecting the outer extremities of said arch shaped portions to said outrigger so as to apply some of the weight of said motors thereon.

3. A vehicle chassis including a longitudinal frame member, a transverse motor support including a channel bar having an arch shaped portion for receiving a motor, the lower side of said arch shaped portion being open so as to permit installation and removal of said motor from below said chassis, upright gusset plates on the respectively opposite sides of said channel bar, and an outrigger secured to the upper extremities of said gusset plates forming a support for a vehicle body.

4. A vehicle chassis including a longitudinal frame member, a transverse motor support including a channel bar having an arch shaped portion for receiving a motor, the lower side of said arch shaped portion being open so as to permit installation and removal of said motor from below said chassis, upright gusset plates on the respectively opposite sides of said channel bar, and a body supporting outrigger comprising a channel bar mounted on said gusset plates, the channel bars of said motor support and outrigger respectively and the gusset plates connecting the latter forming a tubular structure.

5. A vehicle chassis including a central, longitudinal column having channel shaped side members, a motor support mounted on said column and extending laterally beyond the sides thereof, downwardly extending sections on the outer extremities of said motor support, motor mounting brackets secured to the channel shaped side members of said column, and a pair of motors, each secured at one side to one of said brackets and at the other side to one of the downwardly extending sections of said support respectively.

6. A vehicle chassis including a central, longitudinal frame member, a pair of spaced transverse motor supports, each extending beyond the sides of said frame member and comprising a channel bar having downwardly extending end sections, a pair of motors, one located between each side of said frame member and the corresponding downwardly extending sections of said supports, a pair of outriggers in registration with said supports each comprising an inverted channel bar, gusset plates connecting the intermediate portions of the sides of said channel bars together, and means connecting the ends of said motor supports to said outriggers.
